O. A. ROSS

MUSICAL INSTRUMENT

Filed March 4, 1927

UNITED STATES PATENT OFFICE.

OSCAR A. ROSS, OF NEW YORK, N. Y.

MUSICAL INSTRUMENT.

Application filed March 4, 1927. Serial No. 172,755.

This invention relates to musical instruments and more particularly to that class which employs vibrating reeds for producing imitations of the human singing voice.

5 Musical tones resembling the human voice has been produced by rubbing the rosined bow of horse hair strings across the back edge of a carpenter's saw. This operation requires a great physical effort on the part of the operator and his appearance during the rendering 10 of the music is very awkward.

One object of this invention is to furnish a musical instrument which will render pleasing musical tones resembling the human voice 15 without requiring any great physical effort on the part of the operator of the instrument.

Another object is to furnish a musical instrument capable of producing tones similar to the human singing voice, but of a quality 20 more adaptable for reception and broadcasting by radio transmission.

Another object is to produce a musical instrument of pronounced characteristics sufficient in themselves without accompaniment 25 to command the respectful attention of an audience in the same manner as a high salaried artist, however being so simple in operation that any person having a good musical ear may operate the instrument efficiently after a 30 comparatively short period of instruction.

Other objects and advantages will appear as the description of the invention progresses and the novel features of the invention will be pointed out in the appended claims.

35 The invention consists of the novel construction and arrangement of parts herein-after described, delineated in the accompanying drawing and particularly pointed out in that portion of the instrument wherein patentable novelty is claimed for certain and peculiar features of the device, it being understood that, within the scope of what herein-after thus is claimed, divers changes in the 40 form, proportions, size and minor details of the structure may be made without departing from the spirit of, or sacrificing any of the 45 details of the invention.

In describing the invention in detail, reference is made to the accompanying drawings, wherein I have illustrated embodiments 50 of the invention, and wherein like characters of reference, designate corresponding parts throughout the several views, and in which:—

55 Figure 1, is a side elevational view of the preferred form of the invention taken on line

A—A of Fig. 2, and Fig. 2, is a top elevational view of the same instrument taken on line B—B of Fig. 1, and Fig. 3, is a sectional view taken on line C—C of Fig. 1.

Suitably secured to base 1, and braced by 60 brackets 2—2, is standard 3, and to which is secured dial 4 pivotally supporting shaft 5, one end of which carries pointer 6, and the other pinion 7 meshing with rack 8 attached to rod 9 passing through bearing 9^a, and normally impinging on extension 10, of lever 11 by action of spring 12.

Also attached to standard 3, by screws 13—13, is stationary member 14, to which is hinged, by pin 15, the movable member 16 70 having slot 17, into which bolts 18—18 securely clamp one end of vibrating reed, or blade 19, the other end being likewise clamped in slot 20 of the member 21 pivotally supported to the upper end of the link member 23 by 75 pin 22.

Also secured to base 1, by bolts 25—25, is the bearing bracket 26 supporting pin 27, pivotally mounted on which are the lower ends of the link member 23, and the fulcrum 28 of 80 lever 11. Lever 11 also has extremity or extension 29, terminating in foot, or hand operating pad 30, also slot 31 in which is adjustably secured, by bolt 32 and nut 33, the lower end of ribbon, or flexible member 34, the upper 85 end of which passes through pin 35 pivoted in member 21, and is adjusted therewith by nut 36.

Lever 11 also has extension 38 supporting one end of spring 39, the tension of which 90 may be adjusted by screw 40 and lock nut 41. The other end of spring 39 impinges in the recess of boss 24 of link member 23.

Lever 11 also has attached thereto adjusting screw 42 and lock nut 43, screw 42 impinging on plate 44 secured to base 1, said plate 95 acting as the stop for screw 42, and normal adjustment of lever 11.

Also secured to base 1, is bracket 55, having pin 56 pivotally mounted on which, are levers 57—57 having slots 58—58 mid-way and in which operate sleeves 59—59 also adjustably secured in slot 31 and clamped to extension 29 by bolt 60 and nut 61. Levers 57—57 also have slots 62—62 for adjustably securing counter-weights 63—63, secured to levers 57—57 by bolt 64, nut 65 and spacer sleeve 66. Levers 57—57 may have the upper ends terminated in the form of a handle as 68, and the instrument operated thereby. A spring as 67 110

may be interposed between base 1 and levers 57-57 to assist, or entirely replace said weights.

Also secured to standard 3, is bracket 46 supporting motor 47, to the shaft of which is secured crank 48 pivotally supporting one end of rod 49 having turnbuckle 50, and the other end of which is suitably secured to flexible member 34.

10 The operation of the improved musical instrument is as follows: a violin, cello, or other rosined bow, as, 52 having preferably rosined horse hair, is drawn across the edge 53 of the reed 19 causing it to vibrate and produce a musical sound resembling the human voice. However before such a tone can be produced in this manner, the spring 39 must impinge against link member and produce a tension in reed 19, the pitch of the tone produced being dependent largely on this tension, much in the same manner as the pitch of a tone of a piano or other musical instrument string, is largely dependent upon the tension placed between its ends. The normal tension of 25 spring 39 is preferably adjusted such that the tone produced with lever 11 in normal position will be C an octave below what is known as middle C of a piano and corresponding to approximately vibrations per minute. This tone will be produced with the parts as normally shown in Figs. 1, 2, and 3 of the accompanying drawing.

To produce an ascending musical scale from the lowest tone, the pedal 30 is depressed until 35 extension 10 has caused rod 9 and rack 8, to rotate gear 7 and pointer 6 to the following note (D) on the dial 4. The rosined bow 52 is now drawn across the edge 53 at the D position and a musical tone of D pitch will be 40 produced, this tone resembling in quality the human voice.

For each further ascending tones, pedal 30 is further depressed to the pointer indication of each succeeding note and the bow 52 drawn 45 across edge 53 as heretofore described. Obviously selected tones may be produced, these being in the order of some musical composition as may be selected by the operator.

Depression of pedal 30 from line X to line 50 Y, in addition to actuating pointer 6, as hereinbefore described, also compresses spring 39, thereby producing greater tension on reed 19 and the characteristics of spring 39 is such that, as lever 11 is moved from the normal 55 position to the extreme position line Y, and at which time the pointer 6 will be indicating high C, the increase of compression will be such that proper tension of reed 19 is produced whereby the desired tone will be produced.

Depression of pedal 30 also causes flexible member 34 to be drawn downward thereby causing the outer end 21^a of member 21 to be drawn downward from line V to line Z thereby producing a bow or deflection of reed 19

as shown in the dotted position of Fig. 1, this deflection assisting in the efficient production of the tones. This deflection is also considered in determining the characteristics of spring 39.

To produce the vibrato effect which is inherent in well trained human voices, the mid-point of flexible member 34 is caused to be reciprocated by the action of motor 47, crank 48 and rod 49, such reciprocation causing an alternate shortening and elongation thereof, this motion in turn causing a reciprocation of member 21 and reed 19 with a resulting vibrato of the tone produced by reed 19, this vibrato being substantially synchronous with the reciprocation of the flexible member 34.

Adjusting screw 42 and nut 43 serve to adjust for the lowest, or normal tone position of the instrument.

The spacing of the lines indicating the 85 pitch tones on dial 4 and reed 19, is determined by test of the instrument for each tone required, and said spacing is ordinarily of a varied distance and not equidistant as shown.

Counter-weights 63-63 are preferably of 90 such weight, that in normal position, (line T), their effect on extension 29 through the fulcrum formed by bolt 60, is such, that, it nearly neutralizes the effect of spring 39, through extension 38 to seat lever 11 onto plate 44. As the extension 29 is lowered to line Y, the levers 57-57 and counter weights 63-63 move to line U. It will be apparent that as levers 57-57 move to the U position the counter weighting leverage increases producing increased torque on extension 29. This increase of torque is preferably such that it compensates for the increased pressure and resulting torque produced by spring 39 as it is compressed by depression of pedal 30 resulting in lowering of extension 29. By this arrangement very little effort is required to depress pedal 30, or handle 68 to a position for any tone which may be selected on dial 4. An operator, or musician may therefore operate the instrument for a considerable period of time without becoming fatigued.

The mechanism, with the exception of the operating handles 30 and 68 are enclosed in an ornamental case not shown, preferably of 115 suitable resonating material which enriches and mellows the tones produced by the instrument as reed 19 vibrates.

What I claim is:—

1. A bowed musical instrument comprising 120 a tone producing reed, means for supporting each end thereof whereby the unsupported portion thereof is arranged to be tensioned and means affecting the supporting means for varying the degree of tension to produce 125 varying pitch tones as the rosined bow is drawn across the tensioned portion of the reed.

2. A bowed musical instrument comprising 130 a tone producing reed, means for supporting

each end thereof whereby the unsupported portion thereof is arranged to be deflected from its normal position, and means affecting the supporting means for varying the degree 5 of deflection to produce varying pitch tones as the rosined bow is drawn across the unsupported portion of the reed.

3. A bowed musical instrument comprising a tone producing reed, means for supporting each end thereof whereby the unsupported portion thereof is arranged to be jointly tensioned and deflected, means affecting the supporting means for varying the degree of tension and deflection whereby varied pitch tones may be produced as the bow is drawn across the unsupported portion of the reed.

4. A bowed musical instrument comprising a tone producing reed, means for supporting each end thereof whereby the unsupported portion thereof is arranged to be tensioned, means affecting the supporting means for varying the degree of the tension whereby varying pitch tones are produced as the rosined bow is drawn across the unsupported portion, and means for producing a vibration of the reed for producing a vibrato effect of the tone independently of the tone vibration produced by drawing the bow across the unsupported portion of the reed.

30 5. A bowed musical instrument comprising, a tone producing reed, means for supporting the reed by each end thereof, and means affecting the supporting means for variably deflecting the reed between the ends 35 thereof to produce different pitch tones as the bow is drawn across the deflected portion of the reed.

6. A bowed musical instrument comprising, a tone producing reed, means for supporting the reed by each end thereof, and means affecting the supporting means for variably tensioning the reed along its longitudinal axis to produce different pitch tones as the bow is drawn across the tensioned 45 portion of the reed.

7. A bowed musical instrument comprising, a tone producing reed, means for supporting the reed by each end thereof, and means affecting the supporting means for jointly variably deflecting and variably tensioning the reed to produce different pitch tones as the bow is drawn across the unsupported portion of the reed.

8. A bowed musical instrument comprising, a tone producing reed, means for supporting the reed by each end thereof, means affecting the supporting means for variably deflecting the reed between the ends thereof to produce different pitch tones as the bow 55 is drawn across the deflected portion of the reed and means affecting the supporting means for vibrating the reed independently of the tone vibrations produced by the bow whereby a vibrato effect of the tone vibration 60 is produced.

9. A bowed musical instrument comprising, a tone producing reed, means for supporting the reed by each end thereof, means affecting the supporting means for tensioning the reed along its longitudinal axis to 70 produce different pitch tones as the bow is drawn across the tensioned portion of the reed and means affecting the supporting means for vibrating the reed independently of the tone vibrations produced by the bow 75 whereby a vibrato effect of the tone vibration is produced.

10. A bowed musical instrument comprising, a tone producing reed, means for supporting the reed by each end thereof, means for affecting the supporting means for variably deflecting the reed between the ends thereof to produce different pitch tones as the bow is drawn across the deflected portion of the reed, and means actuated by the variable deflecting means for indicating the pitch 80 of tone produced by the reed as a tone is produced thereby.

11. A bowed musical instrument comprising, a tone producing reed, means for supporting the reed by each end thereof, means affecting the supporting means for variably tensioning the reed along its longitudinal axis to produce different pitch tones as the bow is drawn across the tensioned portion 90 of the reed, and means actuated by the variable tensioning means for indicating the pitch of the tone produced by the reed as a tone is produced thereby.

12. A bowed musical instrument comprising, a tone producing reed, means for supporting the reed by each end thereof, means affecting the supporting means for jointly variably deflecting and variably tensioning the reed to produce different pitch tones as 105 the bow is drawn across the unsupported portion of the reed, and means affected by the joint means for indicating the pitch of the tone produced by the reed as a tone is produced thereby.

13. A bowed musical instrument comprising, a tone producing reed, means for supporting the reed by each end thereof, means affecting the supporting means for jointly variably deflecting and variably tensioning the reed to produce different pitch tones as the bow is drawn across the unsupported portion of the reed, means affected by the joint means for indicating the pitch of the tone produced by the reed as a tone is produced 115 thereby, and manually operated means for actuating the joint means.

14. A bowed musical instrument comprising, a substantially flat tone producing reed, means for supporting the reed by each end thereof whereby the unsupported portion thereof is arranged to be tensioned, means affecting the supporting means for varying the degree of tension thereof whereby varying pitch tones are produced as the rosined bow is 125 130

drawn across the unsupported portion, and manually operated means for actuating the tension varying means.

15. A bowed musical instrument comprising, a substantially flat tone producing reed, means for supporting the reed by each end thereof whereby the unsupported portion thereof is deflected from its normal position, means for affecting the supporting means for varying the degree of deflection to produce varying pitch musical tones as the rosined bow is drawn across the unsupported portion, and manually operated means for actuating the deflection varying means.

15. 16. A bowed musical instrument comprising, a substantially flat tone producing reed, means for supporting the reed by each end thereof whereby the unsupported portion thereof is arranged to be jointly tensioned and deflected, means affecting the supporting means for varying the degree of tension and deflection whereby varied pitch tones are produced as the bow is drawn across the unsupported portion, and manually operated means for actuating the joint means.

17. A bowed musical instrument comprising, a substantially flat tone producing reed, means for supporting the reed by each end thereof whereby the unsupported portion thereof is arranged to be jointly tensioned and deflected, means affecting the supporting means for varying the degree of tension and deflection whereby varied pitch tones are produced as the bow is drawn across the unsupported portion of the reed, means for affecting the supporting means whereby a vibration of the reed is produced independently of the tone vibration to produce a vibrato effect of the tone, and manually operated means for actuating the joint means.

18. A bowed musical instrument comprising, a substantially flat tone producing reed, means for supporting the reed by each end thereof whereby the unsupported portion thereof is arranged to be jointly tensioned and deflected, means affecting the supporting

means for varying the degree of tension and deflection whereby varied pitch tone are produced as the bow is drawn across the unsupported portion, means for affecting the supporting means whereby a vibration of the reed is produced independently of the tone vibration to produce a vibrato effect thereof, means for indicating the pitch of the tone produced, and manually operated means for actuating the joint means and the indicating means.

19. A bowed musical instrument comprising, a tone producing reed, means for supporting the reed by each end thereof, means affecting the supporting means for variably deflecting the unsupported portion of the reed between the ends thereof to produce varied pitch tones as the bow is drawn across the unsupported portion and means for adjusting the normal deflected position of the reed.

20. A bowed musical instrument comprising, a tone producing reed, means for supporting the reed by each end thereof, means affecting the supporting means for variably tensioning the unsupported portion of the reed to produce varied pitch tones as the bow is drawn across the unsupported portion and means for adjusting the normal tension of the unsupported portion.

21. A bowed musical instrument comprising, a tone producing reed, means for supporting the reed by each end thereof, means affecting the supporting means for variably tensioning and variably deflecting the unsupported portion of the reed to produce different pitch tones as the bow is drawn across the unsupported portion, means for adjusting the normal tension of the unsupported portion, and means for adjusting the normal deflection independently of the normal tension adjusting means.

Signed at New York, in the county of New York, and State of New York, this 25th day of February, A. D. 1927.

OSCAR A. ROSS.
